UNITED STATES PATENT OFFICE.

WILLIAM C. FARNUM, OF ARLINGTON, VERMONT, ASSIGNOR TO UNION TYPEWRITER COMPANY, OF JERSEY CITY, NEW JERSEY, A CORPORATION OF NEW JERSEY.

TYPE-WRITING MACHINE.

SPECIFICATION forming part of Letters Patent No. 752,214, dated February 16, 1904.

Application filed November 20, 1901. Serial No. 83,010. (No model.)

To all whom it may concern:

Be it known that I, WILLIAM C. FARNUM, a citizen of the United States, and a resident of Arlington, in the county of Bennington and State of Vermont, have invented certain new and useful Improvements in Type-Writing Machines, of which the following is a specification.

My invention relates to what may be termed "auxiliary platen-feed or rotating mechanism for type-writing machines" and which is employed in addition to the ordinary line-spacing mechanism and by which the platen may be rotated in either direction to any extent independently of the ordinary line-spacing mechanism to bring any desired portion of the paper to the printing-line. The auxiliary platen-feed mechanism is particularly available for irregular line-spacing or for filling in partly-printed blanks.

The object of my invention is to provide a simple and efficient device of the character described.

To the above and other ends, which will hereinafter appear, my invention consists in the novel arrangement and combinations of parts and the various details of construction herein-after described, and particularly pointed out in the appended claims.

In the accompanying drawings, wherein like reference characters indicate corresponding parts in the various views, Figure 1 is a top view of a platen-frame and platen embodying my invention, the invention being shown in its application to the platen and frame of a No. 6 Remington type-writing machine. Fig. 2 is a fragmentary sectional view taken on the line $\alpha\alpha$ of Fig. 5 and looking in the direction of the arrow in said figure. Figs. 3 and 4 are detail end and side views, respectively, of the regulating finger-wheel and the eccentric connected thereto. Fig. 5 is an end view of the parts represented in Fig. 1 of the drawings and looking toward the right-hand end of the platen. Fig. 6 is a detail transverse sectional view of the combined finger-wheel and crown-gear. Fig. 7 is an end view of the same, showing the universal or gimbal

joint in place in the finger-wheel, the view being taken in the direction of the arrow in Fig. 5. Fig. 8 is a detail perspective view of the gimbal-joint shown connected to the platen-shaft. Fig. 9 is a detail edge view of one member of the gimbal-joint.

In the platen-frame 1 is mounted a rotating platen 2, which may be provided with the usual finger-wheel 3 at the left-hand end thereof. The right-hand end of the platen-shaft 4 projects beyond the platen-frame and is secured to the platen by a pin 5. The shaft 4 of the platen has a collar 6 thereon, which limits the endwise movement in one direction of a line-spacing wheel 7. This line-spacing wheel 7 rotates freely upon the platen-shaft and is provided with a laterally-extending crown bevel-gear 8. Co-operating with the gear 8 is a bevel-gear 9, which constitutes a part of a cup-shaped finger-wheel 10 and may be termed a "regulating-gear," and the plane of which intersects the plane of the gear 8. This finger-wheel is provided with oppositely-disposed bearings 11 for the reception of the pivots 12 of one member 13 of a gimbal or universal joint. Projecting at right angles to the pivots 12 on said member 13 are pivots 14, that are adapted to be seated within the slotted bearings 15 of the second member 16 of the gimbal-joint. This second member 16 is provided with a collar 17, which surrounds the platen-shaft 4 and is secured thereto by a set-screw 18. The cup-shaped finger-wheel 10 has an opening 19 therein for the reception of the eccentric 20, which is connected to or forms part of the regulating finger-wheel 21. This finger-wheel 21 and eccentric is loosely mounted upon the reduced end 22 of the platen-shaft and is prevented from longitudinal displacement thereon by the shoulder 23, formed by the reduced portion, and by a nut 24, which is secured to the free end of the platen-shaft. The finger-wheel 10 is apertured upon opposite sides at 25 to facilitate the connection between the finger-wheel and the member 13 of the gimbal-joint. The loosely-mounted line-spacing wheel 7 is, as before stated, prevented from longitudinal movement on the shaft

4 in one direction by the collar 6, whereas the collar 17 of the section 16 of the gimbal-joint constitutes an abutment against which a sleeve 26, that projects from the line-spacing wheel, is adapted to abut, so as to prevent movement thereof on the shaft in the opposite direction. The two crown-gears 8 and 9 are provided with different numbers of teeth. Thus we will assume that the crown-gear 8 has 10 thirty-two teeth, in which event the crown-gear 9 may be provided with thirty-three teeth. The member 13 of the gimbal-joint is preferably resilient or flexible to a limited extent and may be sprung into its bearings 11, 15 by which it is connected with the finger-wheel, and when this member is in place in said bearings and the other member, 16, of the joint is forced against the resiliency of the member 13 and is secured in place it tends to deflect 20 the member 13 against its tension, as indicated by the dotted line showing in Fig. 9, and force the teeth of the crown-gear 9 into close contact or engagement with the teeth of the crown-gear 8, so that no lost motion or back-lash may occur between the gears. 25

The line-spacing wheel 7 is provided on its periphery with ratchet-teeth 27, with which a line-spacing pawl 28 co-operates. The pawl 28 is pivotally connected at 29 to an arm 30 of a two-arm spacing-lever which is pivoted to the platen-frame at 31. The other arm, 32, of this two-arm spacing-lever is provided with a finger-piece 33, by means of which it may be vibrated, the parts being restored to 35 normal position by a coiled spring 34, which bears at one end against a pin 35, projecting from the platen-frame, and at its opposite end against a pin 36, that projects from the arm 30 of the spacing-lever. The line-spacing 40 pawl 28 is provided with a depending arm 37, which is adapted to abut against any one of the three faces 38 of a regulating-piece 39, which is pivoted at 40 to the platen-frame and may be provided with suitable means to secure it in any one of the three adjusted positions where the depending arm 37 contacts with one of the faces 38 of this regulating piece or abutment 39 when the parts are in the normal position. In this manner a change in the 45 extent of throw in the line-spacing lever and pawl is effected in order to turn the line-spacing wheel one, two, or three teeth at each operation, as determined by the positioning of the piece 39. In the feed movement of the 50 pawl 28 the depending arm 36 abuts against and is limited by a pin 41, carried by the arm 30. This arm likewise carries a rigid locking-pawl 42, the engaging nose of which will be brought into engagement with the teeth 27 of the 55 line-spacing wheel when the line-spacing pawl reaches the limit of its feed movement, thus locking the line-spacing wheel against further rotation in either direction. Co-operating with the peripheral teeth on the line-spacing 60 wheel 7 is a roller 43, which is carried by a

spring 44, which is secured at 45 to the platen-frame and which presses the roller against the teeth. This spring-pressed roller 40 tends to maintain the line-spacing wheel against accidental displacement. 70

In the operation of the device for ordinary line-spacing a rotation will be transmitted to the line-spacing wheel 7 by the two-arm spacing-lever and a corresponding rotation will be transmitted to the platen 2 by reason of the fact that the gears 8 and 9 are in mesh and adapted to rotate therewith. Should the operator desire to provide a differential spacing—that is to say, to provide a rotating movement of the platen, which differs from that which may be attained with the aid of the line-spacing wheel 7—it is merely necessary to rotate the regulating finger-wheel 21. The effect of this rotation of the regulating finger-wheel is to revolve the eccentric 20, 75 and thereby transmit a movement of nutation to the gear-wheel 9 and its finger-wheel 10, this movement being permitted by the universal-joint connection between the combined crown-gear and finger-wheel and the platen-shaft 4. The movement of nutation of the gear 9 will cause a "rolling" action, so to speak, thereof on the gear 8—that is to say, as the high portion of the inclined eccentric 20 turns the side of the gear 9 next thereto is 80 forced by a swaying action into mesh with the teeth of the gear 8—so that in a complete rotation of the gear 9 every tooth thereof will be successively brought into mesh with the teeth of the gear-wheel 8, and a differential movement between the gear-wheels 8 and 9 is established by the actuation of the finger-wheel 21. The gear-wheel 9 being positively connected to rotate with the platen through its shaft 4 and the gear-wheel 8 being connected to and adapted to revolve with the line-spacing wheel 7 independently of the platen and its shaft, it follows that the turning of the finger-wheel 21 will move the platen 2 and the line-spacing wheel 7 one with relation to the other. In other words, a rotation of the finger-wheel 21 will rotate the platen with relation to the line-spacing wheel when the latter is held against movement. This holding of the line-space wheel is effected by 85 the detent-roller 43, which bears upon the ratchet-teeth under the tension of the spring 44 with sufficient force to hold the wheel against rotation during the movement of the platen in either direction by the finger-wheel 21. 90 The cup-shaped finger-wheel 10, which constitutes a part of or has formed thereon the crown-gear 9, is at all times effective to move the line-spacing wheel and the platen together, and at this time the platen and line-spacing 95 wheel will bear a fixed relation one with the other, because the gears 8 and 9 do not move at this time relatively one to the other. It will be understood from the foregoing description that the combined crown-gear 9 and 100

finger-wheel 10 has two distinct movements—one a movement of nutation, which is effective to provide the differential movement between the line-spacing wheel and the platen, 5 and the other a movement of rotation, which takes place when the line-spacing wheel, platen, and finger-wheel 10 rotate together.

It will be observed that the auxiliary platen-feed mechanism in addition to its employment as a means for rotating the platen independently of the line-spacing mechanism to bring any desired point on the paper to the printing-line is available as a means for distributing the wear on the platen—that is to 15 say, it may be used to change the relative positions of the line-spacing wheel and platen, so that the points of impact of the type on the platen may be changed and the wear distributed over the entire surface instead of on 20 fixed lines, as is ordinarily the case where the line-spacing mechanism alone is employed.

While I have shown and described with considerable detail one form in which my invention may be clothed, it should be understood that various changes in the construction and operation may be made without departing from the spirit of my invention.

What I claim as new, and desire to secure by Letters Patent, is—

30 1. In a type-writing machine, the combination of a platen, a line-spacing ratchet-wheel therefor, a gear-wheel connected to said ratchet-wheel, a regulating-gear positively connected to rotate the platen, and means for 35 effecting a differential movement of said regulating-gear.

2. In a type-writing machine, the combination of a platen, a line-spacing ratchet-wheel therefor, a gear-wheel connected to said 40 ratchet-wheel, a regulating-gear positively connected to rotate the platen, and means for effecting a differential movement of said regulating-gear, said differential movement being independent of the movement of the regulating-gear with the ratchet-wheel.

45 3. In a type-writing machine, the combination of a platen, a line-spacing ratchet-wheel therefor, which is movable independently of said platen, a gear-wheel connected to said ratchet-wheel, a regulating-gear positively connected to rotate the platen and adapted to move independently thereof, and to effect a relative movement between the line-spacing ratchet-wheel and platen, and means for effecting the said independent movement of said regulating-gear.

50 4. In a type-writing machine, the combination of a platen, a line-spacing wheel therefor, a gear-wheel which is operatively connected to the line-spacing wheel, and a regulating-wheel which meshes with said gear-wheel and is movable therewith and has a movement independently thereof.

55 5. In a type-writing machine, the combination of a platen, a line-spacing wheel therefor,

a gear-wheel which is operatively connected to the line-spacing wheel and a regulating-wheel which has a movement of nutation as well as rotation.

6. In a type-writing machine, the combination of a platen, a line-spacing wheel therefor, a gear-wheel which is operatively connected to the line-spacing wheel, a regulating-wheel which meshes with said gear-wheel, and a universal joint between said regulating-wheel 75 and the platen-shaft.

7. In a type-writing machine, the combination of a platen, a line-spacing ratchet-wheel therefor, a gear-wheel which is operatively connected to the line-spacing ratchet-wheel, a regulating-gear which meshes with said gear-wheel and is movable therewith and has a movement independently thereof, and a finger-wheel which constitutes a part of said regulating-gear. 85

8. In a type-writing machine, the combination of a platen, a line-spacing wheel therefor, a gear-wheel which is operatively connected to the line-spacing wheel, a regulating-wheel which has a movement of nutation as well as rotation, and a hand-operated eccentric for transmitting movement to said regulating-wheel. 90

9. In a type-writing machine, the combination of a platen, a line-spacing wheel therefor, a gear-wheel which is operatively connected to the line-spacing wheel, a regulating-wheel which has a movement of nutation as well as rotation, a hand-operated eccentric for transmitting movement to said regulating-wheel, 100 and a universal joint between said regulating-wheel and the platen-shaft. 95

10. In a type-writing machine, the combination of a platen, a line-spacing wheel therefor, a gear-wheel which is operatively connected to the line-spacing wheel, a regulating-wheel which has a movement of nutation as well as rotation, a hand-operated eccentric for transmitting movement to said regulating-wheel, 105 a universal joint between said regulating-wheel and the platen-shaft, and a finger-wheel which constitutes a part of said regulating-wheel. 110

11. In a type-writing machine, the combination of a platen, a line-spacing ratchet-wheel therefor, a toothed gear connected to said ratchet-wheel, a regulating toothed gear which meshes with the gear on the ratchet-wheel, a connection between said regulating-gear and the platen-shaft, whereby said gears, ratchet-wheel and platen are adapted to rotate together, and means for causing the regulating-gear to receive a differential movement with relation to the ratchet-wheel. 115 120

12. In a type-writing machine, the combination of a platen, a line-spacing ratchet-wheel therefor, a toothed gear connected to said ratchet-wheel, a regulating toothed gear which meshes with the gear on the ratchet-wheel and which is operatively connected to the platen- 125 130

shaft, whereby said gears, ratchet-wheel and platen are adapted to rotate together, a universal joint which constitutes the operative connection between said regulating-gear and the platen-shaft, and independent hand-operated means for causing the regulating-gear to receive a differential movement with relation to the ratchet-wheel.

13. In a type-writing machine, the combination of a platen, a line-spacing ratchet-wheel therefor, a toothed gear connected to said ratchet-wheel, a regulating toothed gear which meshes with the gear on the ratchet-wheel and which is operatively connected to the platen-shaft, whereby the said gears, ratchet-wheel and platen are adapted to be rotated together, a universal joint which constitutes the operative connection between the regulating-gear and the platen-shaft, and means for transmitting a movement of nutation to said regulating-gear to effect a displacement of the ratchet-wheel and platen one with relation to the other.

14. In a type-writing machine, the combination of a platen, a platen-shaft secured thereto, a line-spacing ratchet-wheel loosely mounted upon said shaft, a toothed gear upon said ratchet-wheel, a finger-wheel for rotating the platen, a toothed regulating-gear on said finger-wheel and which meshes with the toothed gear on the ratchet-wheel to cause said platen, ratchet and hand wheel to rotate together, a universal joint between said finger-wheel and the platen-shaft, and means for moving said finger-wheel on the universal joint to displace the platen and ratchet-wheel one with relation to the other.

15. In a type-writing machine, the combination of a platen, line-spacing mechanism, a finger-wheel adapted to rotate said platen, said finger-wheel being operatively connected to the platen and to the line-spacing mechanism, and means for producing a separate movement of said finger-wheel to displace the platen and line-spacing mechanism one with relation to the other.

16. In a type-writing machine, the combination of a platen, a finger-wheel connected to move said platen and to have a separate displacing movement with relation thereto, and means for effecting the said displacing movement of the finger-wheel.

17. In a type-writing machine, the combination of a platen, line-spacing mechanism, a finger-wheel connected to move said platen and to have a separate displacing movement with relation thereto, and means for effecting the said displacing movement of the finger-wheel, whereby the platen and line-spacing mechanism will be displaced one with relation to the other.

18. In a type-writing machine, the combination of a platen, a line-spacing ratchet-wheel, a finger-wheel positively connected to the platen so as to turn the same, differential gear

connections between said finger and ratchet wheels, and means for actuating the finger-wheel to effect the differential movement of the parts to displace the platen with relation to the ratchet-wheel.

19. In a type-writing machine, the combination of a platen, a line-spacing ratchet-wheel, a finger-wheel operatively connected to the platen and adapted to rotate with the platen and ratchet-wheel and to have a differential movement with relation to the ratchet-wheel, differential gear connections between said finger and ratchet wheels, and means independent of the finger-wheel for actuating it to effect the differential movement of the parts, to displace the platen with relation to the ratchet-wheel.

20. In a type-writing machine, the combination of a platen, a line-spacing ratchet-wheel, a finger-wheel which is positively connected to rotate the platen, a differential positive connection between the ratchet-wheel and finger-wheel, and means for moving the finger-wheel relatively to the platen to effect a differential movement of the parts, to displace the platen and ratchet-wheel one with relation to the other.

21. In a type-writing machine, the combination of a platen, a line-spacing ratchet-wheel, a gear thereon, a finger-wheel which is positively connected to rotate with the platen, a gear on said finger-wheel and which meshes with the gear on the ratchet-wheel, so as to form a differential connection between the ratchet-wheel and finger-wheel, and means for moving the finger-wheel relatively to the platen, to effect a differential movement of the parts to displace the platen and ratchet-wheel one with relation to the other.

22. In a type-writing machine, the combination of a platen, a line-spacing ratchet-wheel, a finger-wheel which is connected to the platen by a gimbal-joint, a differential connection between the ratchet-wheel and finger-wheel and an eccentric for moving the finger-wheel relatively to the platen, to effect a differential movement of the parts, to displace the platen and ratchet-wheel one with relation to the other.

23. In a type-writing machine, the combination of a platen, a line-spacing ratchet-wheel and its actuating means, a gear thereon, a finger-wheel which is connected to the platen by a gimbal-joint, a gear on said finger-wheel which meshes with the gear on the ratchet-wheel, so as to form a differential connection between the ratchet-wheel and finger-wheel, and an eccentric which is movable independently of the platen for moving the finger-wheel relatively to the platen, to effect a differential movement of the parts, to displace the platen and ratchet-wheel one with relation to the other.

24. In a type-writing machine, the combination of a platen, a line-spacing ratchet-wheel

movable with relation to said platen, a finger-wheel which is operatively connected by a universal joint to rotate with the platen, and means which coöperate with the finger-wheel to effect a displacement of the platen and ratchet-wheel, one with relation to the other when the finger-wheel is moved on its universal joint.

25. In a type-writing machine, the combination of a platen, a ratchet-wheel, a gear-wheel connected thereto, a regulating-gear which is operatively connected to the platen and is mounted in a plane that intersects the plane of the gear on the ratchet-wheel, and means for turning the regulating-gear to produce a differential movement of the platen and ratchet-wheel, one with relation to the other.

26. In a type-writing machine, the combination of a platen, a line-spacing ratchet-wheel having a gear-wheel connected thereto, and a cup-shaped finger-wheel having a crown-gear on the edge thereof that is adapted to coöperate with the gear on the ratchet-wheel and to effect a differential movement of the platen and ratchet-wheel one with relation to the other.

27. In a type-writing machine, the combination of a platen, a line-spacing wheel therefor, a gear-wheel which is operatively connected to the line-spacing wheel, a regulating-wheel which has a movement of nutation as well as
